UNITED STATES PATENT OFFICE.

ALLEN A. BOWSER, OF FORT WAYNE, INDIANA, ASSIGNOR TO S. F. BOWSER & CO. INC.,
OF FORT WAYNE, INDIANA, A CORPORATION OF INDIANA.

AUTOMATIC CUT-OFF FOR MEASURING-PUMPS.

1,052,034.

Specification of Letters Patent.

Patented Feb. 4, 1913.

Application filed July 3, 1907. Serial No. 382,598.

To all whom it may concern:

Be it known that I, ALLEN A. BOWSER, a citizen of the United States, residing at Fort Wayne, in the county of Allen and State of Indiana, have invented certain new and useful Improvements in Automatic Cut-Offs for Measuring-Pumps, of which the following is a specification.

This invention relates to improvements in automatic cut-off for measuring pumps and more particularly to the type of pump described and claimed in the application of H. M. Bowser and Allen A. Bowser filed in the United States Patent Office on or about February 13, 1907, Serial No. 357,125, and also in an application filed by me on or about April 29, 1907, Serial No. 370,996, to which applications reference may be had for the parts not specifically described in the present application, and the primary object of this invention is to provide improved means for automatically cutting off or stopping the action of the pump to prevent the pump from drawing or pumping air when the supply of liquid has been exhausted.

A further object is to provide an improved device of this character which will be simple, cheap and durable in construction, adapted to be readily applied to the pump and effective and efficient in operation.

To the attainment of these ends and the accomplishment of other new and useful objects, as will appear, the invention consists in the features of novelty in the construction, combination and arrangement of the several parts hereinafter more fully described and claimed and shown in the accompanying drawings, illustrating an exemplification of the invention and in which--

Figure 1 is a front elevation, partly in section, of a pump having this improvement applied thereto, constructed in accordance with the principles of this invention. Fig. 2 is a longitudinal sectional view of the vacuum or controlling chamber. Fig. 3 is a diagrammatic view of a portion of the operating mechanism of the pump. Fig. 4 is an elevation, partly in section, of another portion of the operating mechanism.

Referring more particularly to the drawings and in this exemplification of the invention, the numeral 10 designates a suitable supporting base upon which is mounted

a casing 11 and in which casing is mounted the operating mechanism for the pump, and said operating mechanism comprises a sectional shaft, the sections 12, 13 of which are connected by clutch members 14. Mounted upon the section 13 is pulley 15 and secured to the section 12 is a pinion wheel 16, which latter meshes with and drives a suitable gear 17 when the clutch members 14 are in operative position to connect the sections 12 and 13 of the shaft. The gear 17 is provided on its rear face with cams 18, 19 and said gear 17 is rotatably mounted upon a suitable axle 20, shown more clearly in Fig. 3 of the drawings.

The numeral 21 designates a dial or indicator which is provided with peripheral teeth 22.

Slidably mounted in the casing 11 and upon a suitable support is a block or member 23, to which is pivotally connected by one end an operating pawl 24, the extremity 25 of which is adapted to engage and rest upon the peripheral teeth 22 of the dial or indicator 21, and 26 designates a retaining pawl also adapted to engage the peripheral teeth 22 to hold the dial or indicator against retrograde motion when the operating pawl 24 is returned to its initial position; and 27 designates a suitable handle for releasing the pawl 24. The member 23 is provided with a laterally projecting lug or pin 28 adapted to be engaged by the cam 18 to raise the member and the pawl 24 and by the cam 19 to lower the member 23 and pawl 24.

The dial or indicator 21 is provided with a projection 29 extending from the rear face thereof, the extremity of which is adapted to engage one end of a locking pawl 30, which latter is pivotally supported as at 31 and is provided with a projecting portion 32.

The numeral 33 designates a clutch operating member and said member 33 is controlled by an arm or lever 34 which is pivotally supported intermediate its ends as at 35. One extremity of this arm or lever 34 is connected to the clutch operating member 33 by means of a bar or member 36, and said bar or member 36 has a pivotal connection 37 with the arm or lever 34. A suitable flexible member 38, such as a coil spring or the like, is provided for normally holding the clutch operating member 33 in a position to hold the clutch

70

75

80

85

90

95

100

105

110

14 in an inoperative position to disconnect the sections 12, 13 of the shaft. To the free extremity of the arm or lever 34 is pivotally connected one end of a bar or member 39, 5 the upper extremity of which is provided with an off-set or shouldered portion 40, which normally stands adjacent to the locking dog or pawl 30.

A suitable operating lever 41 is provided 10 and adapted to engage one end of the bar or member 39 to raise the same and cause the projecting extremity 40 to rest upon the projecting portion 32 of the locking dog or pawl 30. When this bar or member 39 15 is thus raised and locked by the dog or pawl 30, the clutch operating member 33 will be moved out of operating position to permit the clutch 14 to lock the sections 12 and 13 of the shaft so that motion will be transmitted to the gear 17 and through the medium of the pawl 24 to rotate the dial or indicator 21 and when said dial or indicator 21 has rotated a predetermined distance, the extremity of the projection 29 thereon will 20 engage the extremity of the locking dog or pawl 30 and rock the latter to cause the projecting portion 32 to disengage the portion 40 of the bar or member 39 and permit the yielding member 33 to move the clutch operating member 33 into a position to unlock the clutch members 14 and the sections 25 12 and 13 of the shaft.

All of the above named parts, together with the specific construction and operation 30 thereof form the subject matter of the above named application, Serial No 357,125 and form no part of the present invention.

With this improved construction of 35 pump, and after the dial or indicator has been adjusted in the manner set forth in the above referred to applications, when it is desired to throw the operating mechanism out of operation to prevent the piston 41^a from reciprocating in the cylinder 42 40 a bar or member 43 is provided, one end of which is pivotally connected as at 44 to the locking dog or pawl, and arranged on the free end thereof and in a suitable position to be grasped by the operator is a handle 45, so that when the handle 45 is moved in 45 the proper direction the bar 43 will rock the locking dog 30 about its point of pivotal support 31 to release the bar or member 39.

It sometimes happens that in dispensing 50 quantities of liquid the tank does not contain an amount equal to the amount desired, that is, an amount equal to the amount desired to be pumped or to which the dial or 55 indicator 21 is set, and unless the operator knows exactly the quantity of liquid that is in the tank and he is present at the time the last portion thereof is drawn out of the tank to operate the dog or pawl 30 by means 60 of the handle 45 to cut off the operating

mechanism of the pump, the pump will continue to operate and instead of pumping liquid it will suck in air and will continue to do so until the projection 29 has reached a position to trip the dog or pawl 30. It is the purpose of this invention 70 to provide means for automatically cutting off or stopping the operation of the pump when the supply of liquid has been exhausted regardless of the position of the dial or indicator 21, and the position of the projection 29 with relation to the locking dog or pawl 30, and in this exemplification of the invention a suitable cylinder 46 is provided and said cylinder is connected by 75 means of a pipe 47 to the main pump cylinder 42. A suitable piston 48 is arranged to move within the cylinder 46 and connected to said piston 48 is a piston rod 49 which projects through a suitable aperture 80 in the top 50 of the cylinder and also through a suitable tubular member 51 arranged to communicate with the aperture in the top of the cylinder. A shoulder or projection 52 is provided near the upper 85 extremity of the piston rod 49 and said shoulder or projection is preferably in the form of a sleeve or collar secured in any desired manner to the piston rod.

A bell crank lever 53 is pivotally supported as at 54 to any suitable support adjacent the dog or pawl 30 and one arm of the bell crank 53 is loosely connected to the bar or rod 43 in any desired manner, preferably by means of a pin and slot connection 55, 56. The free extremity of the other arm of the bell crank lever 53 is connected to the free extremity of the piston rod 49, preferably by means of a flexible connection 57; the cylinder 46 being preferably arranged in a direct line with the free extremity of the bell crank lever 53.

A suitable flexible member 58, such as a coil spring or the like, is arranged to surround the tubular member 51 and the piston rod 49 which projects above the head 50 of the cylinder 46, one extremity of said flexible member resting upon the top 50 and the other extremity engaging the shoulder or projection 52 and the tension of said flexible member being such as to normally hold the shoulder or projection 52 slightly spaced above the upper extremity of the tubular member 51, the loose connection of the bell crank lever 53 with the bar or member 43 being adapted to permit an independent movement of said bar or member 43 with relation to the bell crank lever 53 when it is desired to rock the dog or pawl 30 by the member 43.

Connected to the inlet end of the cylinder 42 is a suitable supply pipe 59 which extends into a supply tank 60. Arranged within the tank and preferably supported by the free extremity of the supply pipe 59

70

130

is an arm or member 61 pivotally supported intermediate its ends as at 62.

Supported by one extremity of the arm or member 61 is a suitable valve 63 adapted to engage and close the end of the supply pipe 59 and connected to the free extremity of the arm or member 61 is a float 64. The arm or member 61 is located at a suitable point above the bottom of the tank 60 to permit a free movement of said arm and the float 64 is so arranged with relation to the valve 63 that when a sufficient quantity of liquid is in the tank 60, the float will be raised by the liquid to hold the valve 63 normally open, but when the supply decreases or reaches a certain amount, the float 64 will be lowered and the weight thereof upon the free extremity of the arm or member 61 will seat the valve 63 to close the end of the supply pipe 59. Leading from the cylinder 42, preferably at a point above the piston 41^a is a discharge pipe 65. Assuming the tank 60 to contain an adequate supply of liquid, the float 64 will unseat the valve 63. With the parts in this position, the pump is operated in the same manner as set forth in the applications above referred to. Briefly stated, the operation of this portion of the pump is as follows: When the dial or indicator 21 has been set so that the pump will discharge a predetermined amount and the clutch member 33 has been locked out of operative position so as to join the sections 12 and 13 of the operating shaft motion being applied to this shaft through the medium of a pulley 15, the pinion gear 16 will be rotated, which latter will transmit motion to the gear 17 and through the medium of the member 23, pawls 24 and 26, the dial or indicator 21 will be intermittently rotated until the projection 29 engages and rocks the dog or pawl 30 to release the bar or member 39, which will permit the yielding member 38 to move the clutch operating member 33 into its operating position to unlock the sections 12 and 13 of the shaft. During this operation the piston 48 in the cylinder 46 will be held by means of the yielding member or spring 58 in the position as shown in Figs. 1 and 2 of the drawings, that is, in a position above the bottom of the cylinder 46 so that the shoulder or projection 52 will be spaced above the upper extremity of the tubular member 51, and said yielding member 58 is of such a tension as to hold the piston in this position against the suction ordinarily created by the piston 41^a in the cylinder 42 when the piston is operating, that is, the piston 48 will be balanced by the suction created by the incoming liquid under the influence of the piston 41^a and the yielding member 58 and will be held in this position so long as the valve 63 is unseated. The pin and slot connection 55, 56 of the bell

crank lever 53 and the bar or member 43 will permit the dog or pawl to move independently with relation to the bell crank lever under ordinary conditions. When the supply of liquid is exhausted from the tank 60, the float 64 will descend and the valve 63 will be seated to close the end of the supply pipe 69. When the valve 63 is closed, a further reciprocating of the piston 41^a in the cylinder 42 will create a suction in the pipe 59 and also in the cylinder 46 through the pipe 47, creating a vacuum in said cylinder 46 and drawing upon the piston 48 against the tension of the yielding member 58, and the descent of the piston 48 will, through the medium of the piston rod 49 and flexible connection 57, rock the bell crank lever 53 about its point of pivotal support 54 until one end of the slot 56 engages the pin 55, which will rock the locking dog or pawl 30 upon its point of pivotal support 31 to move its projecting portion 32 out of engagement with the portion 40 of the bar or member 39 to release the clutch member 33 before the projection 29 engages the locking dog 30. The movement of the piston 48 under the influence of the piston 41^a when the valve 63 is closed, is limited by means of the shoulder or projection 52 engaging the free extremity of the tubular member 51 as shown in dotted lines in Fig. 2 of the drawing. When the supply is replenished in the tank 60, the float 64 will unseat the valve 63, which will overcome the vacuum in the cylinder 46 and permit the piston 48 to move to its initial position under the influence of the yielding member or spring 58. Thus it will be seen that with this improved construction the pump will be automatically controlled or cut off when the tank does not contain the required amount of liquid to prevent the pump from pumping or drawing air from the time the liquid has been exhausted until the dial or indicator reaches a position to trip the locking dog.

In order that the invention might be fully understood by those skilled in the art, the details of the foregoing embodiment thereof have been thus specifically described but

What I claim as new and desire to secure by Letters Patent is—

1. In a device of the class described, the combination of a pump provided with an inlet, means for operating the pump, means operating to directly control the inlet and means with which the last said means cooperates for automatically throwing the pump actuating means out of operation when the liquid adjacent the inlet has reached a predetermined level.

2. In a device of the character described, the combination of a pump provided with a liquid supply inlet, means for operating the

70

115

120

125

130

pump, means for controlling said inlet, and means influenced by the supply of fluid for controlling the last said means to control the pump.

5. 3. In a device of the character described, the combination of a pump provided with a fluid supply inlet, means for operating the pump, positive means for throwing the pump out of operation, and fluid actuated 10 means influenced by the supply of fluid for automatically throwing the pump out of operation.

4. In a device of the character described, the combination of a pump provided with 15 an inlet in communication with a source of fluid supply, means for operating the pump, positive means for throwing the pump out of operation, additional means influenced by the fluid for controlling said supply in- 20 let and means controlled by the last said means for throwing the pump out of operation.

5. In a device of the character described, the combination of a tank for containing 25 a supply of liquid, a pump provided with an inlet having communication with the tank, means for operating the pump, a valve for controlling the inlet, a float within the tank, an operative connection between the 30 float and valve whereby the valve will close the inlet when the liquid in the tank reaches a predetermined level, and means controlled by the action of the pump when the valve is closed for automatically throwing said 35 pump out of operation.

6. In a device of the character described, the combination of a tank for containing a supply of liquid, a pump provided with an inlet having communication with the tank, 40 means for operating the pump, positive means for throwing the pump out of operation, a valve for controlling the inlet, a float within the tank, an operative connection between the float and valve whereby the 45 valve will close the inlet when the liquid in the tank reaches a predetermined level, and means controlled by the action of the pump when the valve is closed for automatically throwing said pump out of operation.

50. 7. In a device of the character described, the combination of a pump provided with a supply inlet, means for operating the pump, a counterbalanced member, means whereby the operation of the pump will influence the counterbalanced member to move the same, and means operatively related to the said member whereby the movement of the member under the influence of the pump will throw the pump out of operation.

55. 8. In a device of the character described, the combination of a pump provided with a supply inlet, means for operating the pump, a counterbalanced member, means influenced by the height of the fluid adjacent the inlet 60 whereby the operation of the pump will

influence the counterbalanced member to move the same, and means operatively related to the said member whereby the movement of the member under the influence of the pump will throw the pump out of operation. 70

9. In a device of the character described, the combination of a pump provided with a supply inlet, means for operating the pump, means influenced by the height of the fluid 75 adjacent the inlet for closing said inlet, a counterbalanced member, means for automatically moving said member when the supply inlet is closed, and means controlled by the movement of said member for throwing the pump out of operation. 80

10. In a device of the character described, the combination of a pump provided with a supply inlet, means for operating the pump, a valve for closing the inlet, a chamber having communication with the pump, a member movable in the chamber, means influenced by the height of the liquid adjacent the inlet to close the valve whereby the action of the pump when the valve is 90 closed will move the said member in the chamber, and means influenced by the movement of said member for throwing the pump out of operation. 95

11. In a device of the character described, the combination of a pump provided with a supply inlet, means for operating the pump, a cylinder, a piston movable in said cylinder, means for counterbalancing said piston, said cylinder having communication 100 with the pump, means influenced by the height of the liquid adjacent the inlet for closing the inlet to cause the pump to move the piston in the cylinder and means operatively connected to the piston for throwing the pump out of operation when the said piston is moved under the influence of the pump. 105

12. In a device of the character described, the combination of a pump including a cylinder having a supply inlet, and a piston movable in the cylinder, means for operating the piston, a valve for closing the inlet when the liquid adjacent said inlet has reached a predetermined level, a chamber, 110 a piston movable in said chamber, a yielding member for moving the piston in one direction, said chamber having communication with the pump cylinder whereby the movement of the pump piston will exhaust 115 the fluid from the chamber when the inlet of the pump cylinder is closed to move the piston in the chamber against the tension of the yielding member, and means operatively related to said piston for throwing the pump piston out of operation. 120

13. In a device of the character described, the combination of a pump including a cylinder having a supply inlet, and a piston movable in the cylinder, means for operat- 130

ing the piston, a valve for closing the inlet when the liquid adjacent said inlet has reached a predetermined level, a chamber, a piston movable in said chamber, a yielding member for moving the piston in one direction, said chamber having communication with the pump cylinder whereby the movement of the pump piston will exhaust the fluid from the chamber when the inlet of the pump cylinder is closed to move the piston in the chamber against the tension of the yielding member, means for limiting the movement of the last said piston in one direction, and means operatively related to said piston for throwing the pump piston out of operation.

14. The combination of a pump embodying a liquid extracting means, means for controlling the operation of said liquid extracting means, and means independent of said controlling means whereby the said controlling means are directly actuated by the extracting means to stop the operation of said extracting means when the liquid adjacent the inlet of the pump reaches a predetermined level.

15. The combination of a pump embodying a liquid extracting means, fluid actuated means for controlling the operation of said liquid extracting means, fluid controlled means, and mechanism whereby the second recited means will be directly actuated by the fluid extracting means to stop the operation of said extracting means when the liquid adjacent the inlet of the pump reaches a predetermined level.

16. The combination of a pump embodying a liquid extracting means, and means actuated by a fluid other than the fluid which is extracted, means whereby the last said means will be directly actuated by the said fluid extracting means to stop the op-

eration of said extracting means when the liquid adjacent the inlet of the pump reaches a predetermined level.

17. The combination of a pump embodying a liquid extracting means, means adapted to be actuated by the said extracting means for controlling the operation of the liquid extracting means, and means whereby the said controlling means will be actuated to directly stop the operation of the said extracting means when the liquid adjacent the inlet of the pump reaches a predetermined level.

18. The combination of a pump embodying a liquid extracting means, fluid actuated means for controlling the operation of the liquid extracting means, and means controlled by the liquid whereby the first controlling means will be directly actuated upon by the extracting means to stop the operation of said extracting means when the liquid adjacent the inlet of the pump reaches a predetermined level.

19. The combination of a pump embodying a liquid extracting means, means for controlling the operation of the said liquid extracting means, and means directly operated upon by the said extracting means whereby the second recited means are directly actuated to stop the operation of said extracting means when the liquid adjacent the inlet of the pump reaches a predetermined level.

In testimony whereof I have signed my name to this specification, in the presence of two subscribing witnesses, on this 3rd day of July, A. D., 1907.

ALLEN A. BOWSER.
